UNITED STATES PATENT OFFICE.

GAETANO MARCO, OF DORCHESTER, MASSACHUSETTS, ASSIGNOR TO AMERICAN PIANO COMPANY, OF NEW YORK, N. Y., A CORPORATION OF NEW JERSEY.

ADJUSTABLE HANGER FOR SOSTENUTO DEVICES IN PIANOS.

Application filed April 2, 1921. Serial No. 457,854.

To all whom it may concern:

Be it known that I, GAETANO MARCO, a citizen of the United States, and a resident of the city of Dorchester, county of Suffolk, and State of Massachusetts, have invented an Improvement in Adjustable Hangers for Sostenuto Devices in Pianos, of which the following is a specification.

The present invention relates to piano construction, especially to the construction of the action thereof, and has for an object to provide an improved adjustable hanger adapted to support the sostenuto rod or other similar operative part.

The invention will be best understood from a description of a particular illustrative arrangement embodying the invention, reference being had to the accompanying drawings forming a part hereof and in which:

Figure 1 is a sectional view of a grand piano showing a sostenuto hanger constructed in accordance with the present invention and illustrating its arrangement with respect to the other parts of the piano;

Fig. 2 is a detailed perspective view showing the sostenuto rod and riser with the operative connection therebetween;

Fig. 3 is a detailed view illustrating the relative arrangement of the sostenuto rod and damper operating parts which are arranged to be held in elevated position by the sostenuto rod upon actuation thereof;

Fig. 4 is a transverse elevation showing a sostenuto rod supporting hanger and related parts;

Fig. 5 is a plan view illustrating a preferred arrangement of the hangers supporting the sostenuto rod; and

Fig. 6 is a detail view of the hanger indicating more clearly the position of the point of contact between the parts thereof with respect to the positions of the adjusting screws.

Referring to the drawings I have shown, for the purposes of illustrating the invention, a typical grand piano mechanism including hammers 5 and dampers 6 of common type engaging the strings 7 and operated as usual by the keys 8. A sostenuto rod 9 is arranged when operated to hold elevated selected damper supports to maintain the dampers in retracted position. This rod is rotatably mounted in a series of similar hangers 10, to which hangers the

present invention more particularly relates. The sostenuto rod in operation is rotated by an arm 11 connected to a suitable riser 12, which in turn is operated ordinarily by a pedal (not shown). Rotation of the sostenuto rod brings the lip 13 thereof, Fig. 3, into the path of the felts 14 which project forwardly from the several damper supports. Each damper support comprises a damper wire 15 guided in the damper guide 16, and a lifter member 17 pivotally connected to and guided by a damper lever 18 having one end projecting into the path of the key 8 to be operated thereby simultaneously with the operation of the corresponding hammer 5. This arrangement provides that, as a wire 7 is struck by its hammer, its damper will simultaneously be raised and held raised while the key is held depressed.

In operation, if it is desired to sustain the note or notes struck, the sostenuto pedal is depressed while the key or keys are still held depressed, thus elevating the riser 12 and rotating the sostenuto rod 9 to engage the elevated damper supports and hold the dampers in retracted, inoperative position. If the sostenuto rod is correctly positioned relative to the cooperating parts, the felts of those damper supports which are not elevated will not be engaged by the lip during the rocking movement, as will be obvious from inspection of Fig. 3. Furthermore, while the sostenuto rod is held in operated position to sustain one selected set of dampers, the felt of a subsequently raised damper support will engage only the under side of the lip and will bend sufficiently to permit the usual operation of the damper without being so engaged as to prevent retraction when the corresponding key is released. To obtain reliably and effectively the described operation, the sostenuto rod must be accurately positioned and provision should preferably be made for moving the rod closer to the damper supports when the felts become worn and more flexible. In the illustrated arrangement this is accomplished by providing a number of suitably spaced two-part hangers 10 attached, preferably adjustably, to a convenient support such as the top belly bar 20.

As shown, each hanger comprises a base member 21, a rod-supporting member 22 connected thereto, and means for holding it in adjusted position. The base member is

shown as slotted at 35, Fig. 4, to permit adjustable attachment to its support. As shown, the rod-supporting member is in effect a bell-crank lever bearing against the base member at 23. Screws 24, 25 acting in opposition to each other maintain the rod-supporting member in firm contact with the base member and hold it in adjusted position. In the arrangement shown the type of lever and the positioning of the screws relative to the lever fulcrum are such that both screws are in tension but it is to be understood that this particular arrangement is merely illustrative. The screws extend loosely through slightly elongated holes in the rod supporting member and screw into tapped holes in the base member. A jaw member 26 secured by a screw 27 cooperates with a correspondingly formed jaw 28 of the rod-supporting member 22 to provide a suitable bearing for the sostenuto rod 9.

As shown, the pivot point of the bell-crank member is relatively close to one screw and the adjustment is made mainly by adjustment of the other screw. In fact, the rod-supporting member 22 may be treated as pivoted to the base member. The lower end 30 of the base member 21 may conveniently be bent outwardly, as shown, to bring the same closer to the position of the supported rod to permit the use of a short screw between the rod-supporting member and base member.

The described arrangement provides a simple and conveniently adjusted support for a sostenuto rod and one which may be easily positioned and easily adjusted as occasion requires and the hangers are of the form which can be economically manufactured. The slot in the base member provides for vertical adjustment of the supported rod and the relative adjustability of the hanger members provides for horizontal adjustment toward and from the damper supports.

It is one of the features of the illustrated construction that the adjusting screws can be reached from the front. For example, if it is desired to move the sostenuto rod closer to the damper supports this can be done by tightening the screws 25 by means of a long screw-driver from the front while the action is in place in the piano.

If desired, all dampers may be elevated simultaneously by means of a lever board 32 operated by a suitable control. It is to be noted that there is no interference between the sostenuto arrangement and the lever board arrangement. Whatever the position of the sostenuto rod the lever board may freely operate to hold all dampers in elevated position.

It is to be understood that the construction shown is merely illustrative as the invention may be embodied in various forms

without departing from the scope of the invention as defined in the subjoined claims.

What I claim is:

1. In a grand piano, the combination with a set of dampers, supports therefor and means for moving selected supports to carry corresponding dampers to an inoperative position, and a sostenuto rod movable to engage the selected damper supports to hold the dampers in inoperative position, of a hanger supporting said sostenuto rod comprising a longitudinally adjustable base member and a rod supporting member pivotally adjustable relative to the base member, and means for holding the rod-supporting member in adjusted position. 75

2. In a piano the combination with a sostenuto rod of a two-part hanger therefor, one part being vertically adjustable relative to its support and the other part being movable relative to the first part to provide horizontal adjustment of the supported rod. 85

3. In a piano the combination with a sostenuto rod of a hanger therefor comprising a supporting plate adjustably attached to the piano and a bell-crank lever contacting with the plate and provided with adjusting means located upon opposite sides of said point of contact. 90

4. In a piano the combination with a sostenuto rod of a two-part hanger comprising a base member adjustably attachable to a support, a rod-supporting member constituting a lever fulcrumed against the base member and oppositely acting adjustable means 100 for holding the rod-supporting member in fixed relation to the base member. 95

5. In a piano the combination with a sostenuto rod of a two-part hanger comprising a base member attachable to a support and a rod-supporting member carrying the sostenuto rod to permit operative movement thereof, said rod-supporting member constituting an arm pivoted upon the base member, and adjustable means for holding said rod-supporting member in fixed relation to the base member, whereby the sostenuto rod is afforded an adjustable support. 105 110

6. In a piano the combination with a plurality of damper supports of a sostenuto rod and an adjustable two-part hanger therefor comprising a base member slotted to permit adjustable attachment to a support, a rod-supporting member consisting of a lever bearing against the base member and two screws acting in opposition to each other serving to hold the rod-supporting member in adjustable engagement with the base member. 115 120

7. In a grand piano the combination with a set of dampers, vertically movable supports therefor, means for elevating selected supports to raise corresponding dampers to retracted position and a sostenuto rod movable to engage the elevated supports to 125 130

hold the corresponding dampers in retracted position, of a plurality of hangers supporting said sostenuto rod, each hanger comprising a base member slotted longitudinally 5 to provide vertical adjustment and a rod-supporting member adjustable pivotally relative to the base member and toward and from the damper supports to provide horizontal adjustment for the sostenuto rod and 10 means for holding the rod-supporting member in adjusted position relative to the base member.

8. In a piano having an action with a sostenuto rod, a two-part adjustable hanger, 15 one part attachable to a support within the piano, the other part adjustably connected to the first part and having a bearing for the sostenuto rod, and screw means accessible from the front of the piano to 20 adjust and hold in adjusted position the adjustable part.

9. In a piano having an action with a sostenuto rod, a two-part hanger, one part being adjustably attachable to a vertical 25 support within the piano, the other part being pivotally connected thereto and having a bearing at one end for the sostenuto rod and screw means accessible from the front of the piano adapted to adjust the 30 second part to adjust horizontally the position of said bearing.

10. In a piano having an action and behind the same a sostenuto rod cooperating with a series of damper lifters, a plurality 35 of hangers arranged to support the sostenuto rod, each hanger comprising a bearing member supporting said sostenuto rod and adjusting devices arranged to adjust said bearing and thereby the sostenuto rod toward and from the damper lifters, said devices presenting tool engaging portions exposed for engagement by a tool extending 40 rearwardly between the parts of the action, whereby the position of the sostenuto rod 45 can be adjusted while the action is in place.

11. In a piano having an action and behind the same a sostenuto rod cooperating with a series of damper lifters, a plurality 50 of two-part hangers arranged to support the sostenuto rod, one part of each hanger being secured to the piano frame, the other part supporting the sostenuto rod and being adjustable horizontally to move the sostenuto rod toward and from the damper 55 lifters, adjusting devices connecting said hanger parts and presenting tool engaging parts exposed for engagement by a tool extending rearwardly through the piano action, whereby the position of the sostenuto 60 rod can be adjusted while the piano action is in place.

12. In a piano having an action and be-

hind the same a sostenuto rod cooperating with a series of damper lifters, a plurality 65 of hangers arranged to support the sostenuto rod, each hanger comprising a supporting plate adjustably attached to the piano frame, a bell crank lever contacting with the plate, and adjusting screws located on opposite sides of the point of contact and 70 presenting tool engaging portions exposed for engagement by a tool extending rearwardly between the parts of the action, whereby the position of the sostenuto rod can be adjusted while the piano action is 75 in place.

13. In a piano having an action and behind the same a sostenuto rod cooperating with a series of damper lifters, a plurality 80 of hangers arranged to support the sostenuto rod, each hanger comprising a bearing for the sostenuto rod and adjusting devices for adjusting said sostenuto rod toward and from the damper lifters, said devices having tool engaging portions exposed 85 for engagement from the front of the piano by a tool extending rearwardly through the action, whereby the position of the sostenuto rod can be adjusted from the front 90 of the piano while the action is in place.

14. In a piano having an action and behind the same a sostenuto rod cooperating with a series of damper lifters, a plurality 95 of two-part hangers arranged to support the sostenuto rod, each hanger comprising a part adjustably secured to the piano frame, a part having a bearing for the sostenuto rod and adjustable means for securing the second part to the first part, said means presenting tool engaging adjusting parts 100 exposed for engagement by a tool extending backward through the action whereby the position of the sostenuto rod may be adjusted while the action is in place.

15. In a piano having a sostenuto rod, a two-part hanger for supporting said sostenuto rod, one part constituting the base member and the other part constituting a bearing member affording support for the sostenuto rod having a pivotal engagement 105 against the base member, a screw close to the point of pivotal engagement on one side thereof holding the two parts together and a screw at a distance from the said point of pivotal engagement on the opposite side 110 thereof, also holding the two parts together, the two screws constituting means for adjusting the relation of the bearing member 115 to the base member.

In testimony whereof, I have signed my 120 name to this specification this 30th day of March, 1921.

GAETANO MARCO.
